UNITED STATES PATENT OFFICE.

GOTTFRIED STUPAR, OF CHICAGO, ILLINOIS.

PHONOGRAPH.

1,390,655.

Specification of Letters Patent. Patented Sept. 13, 1921.

Application filed June 26, 1920. Serial No. 391,940.

To all whom it may concern:

Be it known that I, GOTTFRIED STUPAR, a citizen of the United States, residing at Chicago, in the county of Cook and State of Illinois, have invented certain new and useful Improvements in Phonographs, of which the following is a specification.

The invention relates to improvements in phonographs and has especial reference to 10 the construction of the tone block or sound conduit located between the tone arm and the horn.

One of the objects of the invention is to reduce the cost of manufacture of phonograph 15 instruments.

Another object is to provide a simplified means for modifying the sound of such instruments.

Another object is to provide a vertical 20 sound conduit, leading from the tone arm to the horn, composed of two pieces made in a single length, subsequently cut to size and in which two duplicate parts are suitably joined together.

25 Other, further and more specific objects of the invention will become readily apparent, to persons skilled in the art, from a consideration of the following description when taken in conjunction with the drawings, 30 wherein:—

Figure 1 is a section through a fragment of a phonograph casing showing my tone block or sound conduit and modifier in place.

Fig. 2 is an enlarged section taken on line 35 2—2 of Fig. 1.

Fig. 3 is an enlarged section, similar to Fig. 1, showing the sound conduit fully open.

Fig. 4 is a similar view showing the sound 40 conduit fully closed by the modifier.

Fig. 5 is a side elevation of one-half of the conduit structure which is a duplicate of the other half.

In all the views the same reference characters are employed to indicate similar parts.

In most phonograph structures, of the disk type, there are, located in the casing of the structure, a tone arm, which carries the sound box; a horn from which the sound is issued and a tone block or conduit connecting the tone arm to the horn. In some such structures the large end of the horn is closed, to a greater or less degree, by the use of hinged doors for the purpose of modifying 50 the sound. In my improved structure, I

modify the sound by means of a constricting device located in the sound conduit.

In the specific structure illustrated, 10 is a phonograph casing, having a motor board 11 and a horn chamber 12. The motor 13 is 60 employed to rotate the table 15. A horn 16 is located in the horn chamber 12, its larger end extending toward the front and its smaller end, toward the rear of the casing 10. A swiveling tone arm 17 is located in 65 the usual position with its lower open end 18 located practically immediately above the small end 19 of the horn 16. A tone block or sound conduit 20 is employed for conducting the sound from the tone arm 17 into the 70 horn. In the particular structure illustrated the conduit consists of two duplicate parts 21 and 21^a. Originally the members 21 and 21^a were parts of the same elongated strip, 75 in which the tongue 22 was on one side and the groove 23 in which the tongue is to be included, on the opposite side of the strip. In making the conduit 20, I take a strip of wood, of suitable dimensions, and on a 80 sticker I fashion the groove 24, which is preferably semi-circular in form, and simultaneously I fashion the tongue 22 on one side of the strip and the groove in which the tongue is to be received, on the opposite side, so that when the strip is cut in suitable 85 lengths, the two duplicate parts will go together, and, when placing glue around the tongue and within the groove 22 and 23, the parts may be secured together as one piece and the opening 25 will then be of circular 90 form. Near the lower end, 26, of the structure 20, I bore a transverse hole 27, which bisects the bore 25 and communicates with the interior of the horn 16. Hole 27, on one side of passage 25, serves to interconnect the 95 horn and the sound passage, and, on the other side serves as a journal or support for a rotatable sound controlling valve, to be hereinafter described. Before boring the hole 27, however, I place a plug 28 in the 100 bore 25 and bore the hole through the plug at the same time the hole is bored through the members 21 and 21^a. A valve in the form of a wooden shaft 29, fitting neatly in the hole 27, has its front end cut obliquely on a 105 curved line 30, producing a concaved depression 31 which conforms with the radial dimensions of the bore 25. It will be observed, by looking at Fig. 3, that the line 30 defines the opening from 25 to 27, on a curve, 110

so that the sound coming from the tone arm 17 to conduit 20, striking the curve 30, will be projected into the interior of the horn 16 without producing echo. When the shaft 5 29 is rotated 180 degrees, into position shown in Fig. 4, the opening 25 is completely closed so that no sound will issue from the front end of the horn. The sound may be modified to a greater or less extent by rotating the 10 shaft 29 into any position intermediate of the position shown in Figs. 3 and 4. The shaft 29 is preferably passed through the back wall of the instrument 10, and a washer 15 32 is placed on each side of the wall, being held in place by the pins 34, to cause some friction so that the shaft 29 will remain in the position in which it is moved. A handle 35 is connected to the shaft 29 for the purpose of rotating it. In whatever position 20 the shaft 29 may be placed, the curve 30 will have the effect of smoothly conducting the sound into the horn.

In making the sound conduit 20 it is only necessary to cut the strip, of which the two 25 members 21 and 21^a are made, into uniform lengths and glue the strips together, as shown in Fig. 2, then bore the transverse hole 27 and fit the shaft 29 therein. This is a very simple and inexpensive means of 30 producing the structure and it is very effective in its operation.

Other means than that shown may be employed for rotating the shaft 29 and instead of rotating it, it may be reciprocated and 35 accomplish the same result.

When the conduit is made, in the manner shown, it also serves as a means, to some extent, for supporting the motor board 7 in its place, it rests directly under the motor 40 board and immediately upon the bottom wall of the casing.

Having described my invention what I claim as new and desire to secure by Letters Patent is:—

45 1. A phonograph sound directing device comprising an elongated block having a

sound directing passage extending longitudinally thereof from one end to a point near the opposite end and a transverse opening therethrough intersecting the longitudinal 50 passage adjacent one end thereof, the transverse opening on one side of the intersection co-operating in the directing of sound and on the other side providing a journal for a valve, and a rotatable valve for directing the 55 sound from the passage to the transverse opening and operable to modify the sound passing therethrough.

2. In a phonograph having a movable tone arm and horn, the combination of a wooden block extending between the tone arm and horn and having a longitudinal passage therethrough for interconnecting the tone arm and horn and a transverse opening intersecting the passage, the opening on one 60 side of the intersection serving to direct the sound into the horn and on the other side serving to journal a valve, and a rotatable valve projecting through the journal into the sound passage and having its inner end 65 oblique to the axis so that when turned to different positions the communication between the horn and sound passage will be varied.

3. A phonograph having a movable tone 70 arm and horn in combination with a wooden block having a longitudinally extending passage to conduct sound from the tone arm and an intersecting transverse opening therethrough, said opening on one side of 75 the passage serving to interconnect the passage and horn and on the other side serving as a journal for a valve, a rotatable valve projecting through the opening on the journaling side thereof and into the passage to 80 vary the area of communication between the passage and the horn, and a plug for closing the passage on the side of the valve opposite the tone arm.

In testimony whereof I hereunto subscribe my name.

GOTTFRIED STUPAR.
